UNITED STATES PATENT OFFICE

CHARLES M. PATTY, SR., OF MARSHALL, ARKANSAS, ASSIGNOR OF ONE-HALF TO H. D. WEAVER, OF MARSHALL, ARKANSAS

AUTOMATIC SAFETY DEVICE FOR GAS STOVES

Application filed December 29, 1928. Serial No. 329,118.

The present invention relates to improvements in safety devices for gas stoves and the like, and has for its principal object to provide a device for automatically cutting off the flow of gas to the burner should the burner accidentally blow out.

Another important object is to provide a safety device of the above mentioned character that includes a thermostatic unit for effecting the actuation of the cut-off means in a positive and efficient manner should the light of the burner go out, the device embodying the present invention being of such construction as to permit its installation on the fuel supply pipe of the gas stove without necessitating any material alterations.

Another important object is to provide a safety device that includes a spring controlled cut off valve arranged within the fuel supply pipe, a thermostatically controlled unit being operatively associated with the spring actuated valve for normally holding the same in an open position when the burner is in operation, an auxiliary heating unit being disposed for cooperation with the thermostatic means to maintain the valve holding means in an operative position under normal conditions.

Another important object is to provide a safety device of the above mentioned character that is simple in construction, inexpensive, strong and durable and further well adapted to the purpose for which it is designed.

Other objects and advantages of the invention will become apparent from the following description when taken in connection with the accompanying drawings.

In the accompanying drawings wherein like reference characters indicate corresponding parts throughout the same:

Figure 1 is a side elevation of the safety device embodying my invention showing the same associated with a main fuel supply pipe of a gas stove.

Figure 2 is a vertical sectional view taken approximately on the line 2—2 of Figure 1.

Figure 3 is a top plan view of the invention showing a gas stove burner in association therewith, and

Figure 4 is a sectional view taken approximately on the line 4—4 of Figure 3.

In the drawings wherein for the purpose of illustration is shown the preferred embodiment of my invention, the numeral 1 designates the main gas supply pipe from which extends the jet pipe 2 for supplying gas to the burner 3 which burner may be of the conventional construction such as is found on gas stoves now generally in use.

Arranged in the jet pipe 2 for regulating the supply of the gas to the burner 3 is the rotary valve 4 that includes a rotary plug having an actuating handle 5 associated therewith. This rotary valve is also of the conventional construction, and a detailed description thereof is therefore believed unnecessary in so far as the present invention is concerned.

A valve body 6 is arranged in the main fuel supply pipe 1, and a rotary plug 7 is mounted in the valve body 6 for controlling the flow of the gas through the pipe 1. A horizontally extending arm 8 is formed on the upper end of the rotary plug 7 for actuating the same and the outer end of this arm is provided with an upwardly disposed foot 9, the purpose of which will be presently described.

An axial coil spring 10 encircles the lower projecting end of the plug 7, one end of this spring being connected to the bottom of the valve body 6, while the other end has connection with a cross pin 11 carried by the lower end of the plug 7. This spring normally maintains the rotary plug 7 in a closed position cutting off the supply of the gas through the pipe 1.

Forming a salient part of the present invention is the frame 12 that is secured on the fuel supply pipe 1 by the clamping bands 13 for disposition adjacent the valve body 6 and this frame extends upwardly from the main gas supply pipe 1.

Arranged within the upper portion of the frame 12 is the thermostatic unit denoted generally by the numeral 14, and this thermostatic unit comprises the vertically arranged upper and lower wafers 15 and 16, respectively.

5 An adjusting screw 17 extends through the intermediate portion of the cross bar 18 of the frame 12 for engagement with the central portion of the bottom of the lowermost wafer 16 while extending from the top of the uppermost wafer is the pin 19, the top of the frame 12 being formed with an opening to permit the free vertical movement of this pin therethrough.

10 The lower portion of the pin is formed with an annular groove 20 to accommodate the forked end of a lever 21 that is pivoted at its outer end at one side of the frame 12 for vertical swinging movement.

15 The pivoted end of the lever 21 is formed with a depending angularly disposed trigger 22, the lower end of which is adapted to cooperatively engage with the upstanding foot 9 formed on the outer free end of the arm 8 to 20 hold the spring actuated valve plug 7 in an open position under certain conditions. Suitable guide means shown generally at 23 is associated with the frame and the vertically swinging trigger 22, as indicated in Figures 25 1 and 3.

25 A substantially U-shaped burner 24 is supported on the frame 12 in such a manner that the jets of this U-shaped burner are disposed beneath the bottom of the lowermost wafer 30 16. A gas supply nipple 25 is associated with this U-shaped burner 24, and gas is delivered to this nipple by means of a supply tube 26 that extends from the jet pipe 2. A manually operable valve 27 is arranged in the nipple 25 35 to regulate the supply of gas to the U-shaped burner 24.

When the parts are arranged as shown in Figure 1, the burner 3 is lit as is also the burner 24 and the heat will cause the wafers 40 15 and 16 of the thermostatic unit 14 to expand whereby to maintain the trigger 22 in engagement with the foot 9 so that the valve 7 is held in an open position permitting the gas to be supplied to the main burner 3 while 45 the valve 4 is in an open position. Should the flame of the burner 24 accidentally go out, the wafers 15 and 16 of the thermostatic unit 14 will automatically contract causing a downward movement of the pin 19 with the result 50 that the lever 21 will swing downwardly and at the same time the trigger 22 will swing upwardly out of the path of movement of the foot 9 and the spring 10 will automatically actuate the plug 7 to move the same to a 55 closed position, thereby cutting off supply of the gas to the main burner 3.

By actuating the valve 4 to cut off the supply of the gas to the burner 3 manually, the gas will also be turned off to the U-shaped 60 burner 24.

65 The valve 7 may be again turned to an open position by swinging the arm 8 into position for engagement with the trigger 22 and by igniting the burner 24, the expansion of the 65 thermostatic unit 14 will effect the actuation

of the pivoted lever 21 whereby to maintain the trigger 22 in cooperative engagement with the foot 9 so that said valve plug 7 will be maintained in an open position to permit the flow of the gas through the pipe 1 to the main burner 3, providing of course that the valve 4 is in an open position.

70 The provision of a safety device of the above mentioned character will absolutely prevent the escape of gas in the room, and 75 causing loss of life. Furthermore, the simplicity of my device enables the same to be readily and easily installed on a gas stove without necessitating any material alterations. Also, my device will at all times be 80 positive and efficient in carrying out the purposes for which it is designed.

85 While I have shown the preferred embodiment of my invention, it is to be understood that minor changes in the size, shape and arrangement of parts may be resorted to without departing from the spirit of the invention and the scope of the appended claim.

Having thus described the invention, what I claim as new, and desire to secure by Letters 90 Patent is:—

95 In a safety device of the class described, a gas supply pipe, a rotary valve mounted in the pipe, spring means associated with the rotary valve for normally maintaining the same in a closed position, an arm extending laterally from the upper end of the rotary valve, an upstanding substantially rectangular frame disposed longitudinally on the pipe adjacent the valve, clamping rings integrally connected to the opposite ends of the frame and encircling the pipe for securing said frame thereon, a cross bar extending longitudinally of the frame between the upper and lower ends thereof, a thermal element disposed between the cross bar and the upper end of the frame, means for adjustably mounting the thermal element in the frame, a burner mounted on the frame beneath the thermal element, and a lever operatively connected with the thermal element for actuation thereby to hold said valve in open position.

100 In testimony whereof I affix my signature.

CHARLES M. PATTY, SR.
